DESIGN FOR A RANGE FINDER CASING

Joseph Mihalyi, Rochester, N. Y., assignor to Eastman Kodak Company, Rochester, N. Y., a corporation of New York

Application September 4, 1935, Serial No. 58,424

Term of patent 7 years

To all whom it may concern:

Be it known that I, Joseph Mihalyi, a citizen of the United States, residing at Rochester, in the county of Monroe and State of New York, have invented a new, original, and ornamental Design for a Range Finder Casing, of which the following is a specification, reference being had to the accompanying drawing, forming a part thereof.

In the drawing:

Fig. 1 is a perspective view of the range finder casing showing my new design.

Fig. 2 is a similar view of the range finder casing, but taken from the opposite side from that shown in Fig. 1.

Fig. 3 is a bottom plan view of the range finder casing shown in the preceding figures.

I claim:

The ornamental design for a range finder casing as shown.

Signed at Rochester, New York, this 29th day of August 1935.

JOSEPH MIHALYI.
